United States Patent Office.

SEBEUS C. MAINE, OF BOSTON, MASSACHUSETTS.

Letters Patent No. 80,830, dated August 11, 1868.

IMPROVED FOLDING MOSQUITO-FRAME.

The Schedule referred to in these Letters Patent and making part of the same.

TO ALL WHOM IT MAY CONCERN:

Be it known that I, SEBEUS C. MAINE, of Boston, in the county of Suffolk, and State of Massachusetts, have invented an Improved Folding Frame with Mosquito-Net attached, of which the following is a full, clear, and exact description, reference being had to the accompanying drawings, making a part of this specification; in which—

Figure 1 is a view of a cornice. Between the ends of this cornice (inside) is a roller, described as A. In front of this roller, and to each end of the cornice, are attached the ends of the folding frame, which, in the drawing, is composed of five pieces, two on each side and one in front, and marked B. These pieces are secured together by hinges, and to be attached to the cornice by step or crane-hinges, eyes being secured to the ends of the cornice, so that the frame may be readily shipped and as readily detached. C is the cloth, forming the top and back, and D the mosquito-netting. This figure represents, in perspective, the frame extended.

Figure 2 represents, in perspective, the frame partly closed, thus showing the manner of hinging the frame and the folding of the same.

It will be readily seen that a frame, constructed in this form, may be attached to cabinet or wardrobe-beds or to common bedsteads, by a strip or cornice, extending from one head-post to the others, or from strips attached to the bedstead for that purpose, or a cornice may be attached to the wall in any part of a room, from which a drapery-netting can at any time be extended, thus securing a place for a bed, table, or for any purpose, free from the annoyance of flies or mosquitoes.

To enable others skilled in the art to understand and use my invention, I will now proceed to describe the manner in which I have carried it out.

In the accompanying drawings, figs. 1 and 2, a cornice is represented. This may be made of any size or form desired. Across this cornice, and near the back, I place a roller, like the common curtain-roller; over this roller I place a strip of cloth, of any desirable material, and attach it to the front piece of the frame. This cloth forms, when the frame is extended, the top and back of the space to be protected from flies and mosquitoes. Across the back of this I run a tuck, large enough to admit an iron rod, E, of size sufficient to serve as a weight. Around the three sides of the frame I tack or attach my netting.

When the frame is extended, the weight confines the cloth to the top of the frame, closing all apertures.

The netting, extending to the floor, prevents flies and mosquitoes from entering under it, while the folds in the sides of the netting may be carried behind the back, or secured to it, and the expulsion of insects is thus rendered complete.

Around this netting I have cords attached, appropriately festooned with tassels.

Operation.

Take the centre cord and extend the frame to right angles, secure the sides with hooks at the joints in the centre. The space thus enclosed is ready for use. Again, unfasten the hooks, give the cord a slight motion, and the weight of the rod will fold the drapery to the wall.

What I claim as my invention, and desire to secure by Letters Patent, is—

The folding frame B, with cloth C and netting D attached, in combination with roller A and weight E, the whole operating substantially in the manner and for the purposes specified.
